R. L. TULLIS

AUTOMOBILE DOOR LATCH

Filed July 9, 1923

Inventor
Roland L. Tullis:

By
R. S. Burns
Attorney.

UNITED STATES PATENT OFFICE.

ROLAND L. TULLIS, OF MONROVIA, CALIFORNIA.

AUTOMOBILE DOOR LATCH.

Application filed July 9, 1923. Serial No. 650,308.

To all whom it may concern:

Be it known that I, ROLAND L. TULLIS, a citizen of the United States, residing at Monrovia, in the county of Los Angeles and State of California, have invented new and useful Improvements in Automobile Door Latches, of which the following is a specification.

My invention relates to door latches, and more particularly to door latches applicable to motor vehicles.

The primary object of my invention is to provide an automobile door latch which is so constructed as to hold the door closed in such fashion as to obviate vibration and rattle.

Another object of my invention is to provide a latch in which the bolt is automatically held in withdrawn position when retracted, as in opening a door, and automatically released and advanced when the door is completely closed.

With the foregoing objects in view, together with such other objects and advantages as may subsequently appear, my invention resides in the construction and features illustrated in the accompanying drawings, in which:

Figure 1 is a view in side elevation, and partly in section, of my latch applied to a door, showing the door in closed position.

Fig. 2 is a cross sectional view on the line 2—2 of Fig. 1.

Fig. 3 is a top plan view, partly in section, of my invention as applied to an automobile door, showing the door in closed position.

Fig. 4 is a cross sectional view of the line 4—4 of Fig. 1.

Fig. 5 is a top plan view, partly in section, showing a modified form of handle.

Fig. 6 is a cross sectional view on the line 6—6 of Fig. 5.

More specifically, 7 and 8 indicate the side door frames, and 9 the top section of the frame, which arrangement is the usual form of auto door construction. Mounted between the door frames and secured to the outside door frame 7 is the latch bolt mechanism 12, which comprises a flat plate 13 provided with screw holes for the reception of screws 14 for attaching the plate to the door

frame. Formed integral with the plate, and extending inwardly therefrom is a cylindrical casing 15 open at its forward end and closed at the rear by a wall 16. Mounted for slidable movement within the casing is a latch bolt having a rounded head 17 at its forward end; the rounded head is reduced towards the rear to form an annular shoulder 18 from which shoulder a cylindrical portion 19 extends rearwardly.

The latch bolt is mounted and attached to a rod 20, provided with an enlarged head 21 having an annular groove or recess 22, receiving a pin 23 which passes through the walls of the cylindrical portion 19 of the bolt, and is secured thereto in any desired manner. Thus the bolt is secured to the rod and is held against lateral movement within the casing but is free to turn. Encircling the rod 20 and bearing against the rear end of the cylindrical portion 19 and the rear wall 16 of the cylinder is a spiral spring 24, which spring exerts a pressure against the cylindrical end portion of the bolt to force the bolt outwardly. The rear end of the rod 20 has an elongated slot 25 which is adapted to be engaged by and ride upon a pin 26 carried on and secured to the handle 27 in any desired manner, the handle 27 being pivoted at its lower end to the plate 13 at 28, the upper end of handle extending upwardly through a slot provided in the upper edge of the door. The cylinder on its circumference toward the inner side of the door, is provided with a pivoted dog 29, the dog being mounted on a pivot pin 30 which is journaled into lugs 32 formed integral with the casing 15. To hold the dog under strained tension, the leaf spring 33 is provided, being attached to the inner side of the casing by a screw as at 34 or in any desirable manner. Under the tension of the spring the dog, when free to move, is adapted to engage the shoulder formed on the latch bolt, and as is more clearly shown in Fig. 5, to hold the bolt in retracted position.

For receiving the end of the bolt when the door is in closed position a plate 35 is provided having a depression or socket 36, and is attached to the body frame. The plate 35 on its side toward the inner part of the frame is provided with an outstanding lug

37. The socket is lined with rubber as at 38, but may be lined with any cushioning or sound-deadening material.

When the door is in its innermost or 5 closed position the outer end of the dog strikes against the lug 37, thereby releasing the inner end of dog from the shoulder of the bolt and allowing the bolt to be shot forward by the spring into the socket in the 10 plate; as is more clearly shown in Figs. 1 and 3.

In the modification shown in Fig. 5 the latch-operating handles extend from the sides of the door frame, the handles being 15 connected by a shaft 39 which is journaled in bearings 40, the shaft having securely attached thereto a bifurcated arm 41. In the outer extremities of the bifurcated arm are provided apertures through which a pin 20 is inserted, the pin passing through an elongated slot of the rod and is secured to the bifurcated arms in any desired manner.

In the operation of my latch bolt, to retract the bolt, the hand lever is pulled rearwardly swinging on its pivot, and through 25 the rod pulling the bolt head out of its socket against the action of the spring. The handle is pulled back until the bolt has cleared the plate and socket mounted on the 30 frame, at which time the spring acting upon the dog forces the inner end of the dog into engagement with the shoulder formed on the bolt, when the door may be opened, the bolt being held in retracted position.

35 Upon closing the door or swinging it to its innermost position and the dog and bolt head will pass by the frame and socket plate until the outer end of the dog strikes against the lug formed on the plate, thereby swinging the inner end of the dog outwardly from 40 engagement with the shoulder, whereby the bolt is forced outwardly by the action of the spring into engagement with the socket. The socket conforms to the shape of the bolt 45 head so that when the head is shot into the socket a snug engagement is formed.

Since there is a constant flexing or springing in the frame and body of an automobile which is transferred to the doors, there is 50 also constant wear upon the latch bolts of the usual type of construction. This objection is overcome by the present bolt which rotates in its bearing to compensate for such movement and thereby prevent unequal wear.

While I have shown and described a specific embodiment of my invention, I do not limit myself to the exact construction shown, but may employ such changes and modifications in the construction and arrangement of parts as come within the scope of the appended claims.

I claim:—

1. In a door latch, a bolt, a casing in which 65 said bolt is mounted for rotary and longi-

tudinal movement, a spring for advancing said bolt, means for manually retracting said bolt in opposition to said spring, an annular shoulder on said bolt, a spring pressed dog carried by said casing engageable with said shoulder to hold the bolt in a retracted position, a socket adapted to receive the outer end of said bolt, and means operable to throw said dog out of engagement with said shoulder on moving the bolt laterally 75 whereby the bolt will be released and caused to advance to position its outer end in said socket when the bolt reaches a position in alignment with said socket.

2. In a door latch, a bolt mounted for rotary and longitudinal movement, said bolt being formed with a rounded head, a spring for advancing said bolt, manually operable means for retracting said bolt, a rounded socket adapted to receive said rounded head 85 when said bolt is in its advanced position, and means for holding said bolt in its retracted position operable to release said bolt on moving the bolt laterally to a position opposite said socket. 90

3. In a door latch, a bolt, a spring for advancing said bolt, manually operable means for retracting said bolt, a socket adapted to receive said bolt when in its advanced position, a cushion lining in said socket within 95 which cushion lining the end of the bolt is received, and means for holding said bolt in its retracted position operable to release said bolt on moving the bolt laterally to a position opposite said socket. 100

4. In a door latch, a bolt formed with a rounded head, manually operable means for retracting said bolt, a spring for advancing said bolt, a rounded socket adapted to receive said rounded head when said bolt is 105 in its advanced position, a resilient lining in said rounded socket within which lining the end of the bolt is received, and means for holding said bolt in its retracted position operable to release said bolt on moving the bolt laterally to a position opposite said socket. 110

5. In a door latch, a bolt mounted for rotary and longitudinal movement, said bolt being formed with a rounded head, a spring for advancing said bolt, manually operable means for retracting said bolt, a rounded socket adapted to receive said rounded head when said bolt is in its advanced position, a resilient lining in said rounded socket, and means for holding said bolt in its retracted position operable to release said bolt on moving the bolt laterally to a position opposite said socket. 115

6. In a door latch, a cylindrical casing, a cylindrical bolt slidably and turnably mounted in said casing, a spring in said casing for advancing said bolt, a rounded socket for receiving the end of said bolt when advanced, and means for holding said bolt in 120 125 130

its retracted position operable to release the bolt on moving the bolt opposite said socket.

7. In a door latch, a bolt, a spring for advancing said bolt, manually operable means for retracting said bolt, a socket adapted to receive said bolt when in its advanced position, said bolt being mounted for both rotary and longitudinal movements and means for holding said bolt in its retracted position and operable to release said bolt on moving the bolt laterally to a position opposite said socket. 10

ROLAND L. TULLIS.
